CLAIM

The ornamental design for a grill press as shown and described.

DESCRIPTION

FIG. 1 is a top perspective view a grill press showing my new design;

FIG. 2 is a front elevational view thereof, the rear elevational view being a mirror image;

FIG. 3 is a left end elevational view thereof, the right end elevational view being a mirror image;

FIG. 4 is a top plan view thereof;

FIG. 5 is a bottom plan view thereof;

FIG. 6 is another top perspective view thereof showing the handle of the grill press in a folded down position;

FIG. 7 is another front elevational view thereof showing the handle of the grill press in a folded down position;

FIG. 8 is another end elevational view thereof showing the handle of the grill press in a folded down position;

FIG. 9 is another rear elevational view thereof showing the handle of the grill press in a folded down position;

FIG. 10 is another top plan view thereof showing the handle of the grill press in a folded down position; and,

FIG. 11 is another bottom plan view thereof showing the handle of the grill press in a folded down position.

The detent on the top of the handle of the grill press and the hanger hole near the edge of the bottom plate of the grill press are shown in broken lines for illustrative purposes only and form no part of the claimed claim. The locking sleeves are shown with a symbolic break in FIGS. 1-3, 6, 8 and 10. The appearance of any portion of the article between the break lines forms no part of the claimed design.

1 Claim, 9 Drawing Sheets
